UNITED STATES PATENT OFFICE

MATTHEW K. KUCHINSKY, OF IRVINGTON, NEW JERSEY

SURFACE WASHING MACHINE

Application filed March 15, 1929. Serial No. 347,353.

This invention relates to a washing machine, and particularly to a surface washing machine, the object being to provide an improved construction which may be readily moved over a floor, wall or other surface and clean the surface as it moves.

Another object of the invention is to provide a washing machine for cleaning surfaces, wherein a suction is provided for removing the washing liquid and dirt as the machine moves over the surface.

A further object of the invention, more specifically, is to provide a surface washing machine wherein a rotating brush is used for applying liquid and detergent to a surface while tubular members act as conduits for withdrawing the dirt, water and detergent.

In the accompanying drawings,—

Figure 1 is a plan view of a surface washing machine disclosing an embodiment of the invention;

Figure 2 is a sectional view through Figure 1 approximately on the line 2—2;

Figure 3 is a bottom plan view of the structure shown in Figure 1;

Figure 4 is a sectional view through Figure 2 approximately on the line 4—4;

Figure 5 is a fragmentary sectional view through Figure 1 on the line 5—5;

Figure 6 is a sectional view through Figure 2 on the line 6—6.

Referring to the accompanying drawings by numerals, 1 indicates a metal casing which has been shown rectangular, but which, if desired, may be made of some other shape. This casing is formed with a pair of upstanding ears 2 and 3, each ear being apertured so as to receive the pivotal screws 4 and 5 extending through the arms 6 and 7 of the clamp 8. The clamp 8 is adapted to be clamped to a handle 9, whereby the arms 6 and 7 may function to move the casing 1 around. The ear 3 is provided with notches 10, as shown particularly in Figure 6, and the arm 7 is provided with a number of notches 11, said notches being adapted to register so that a locking pin 12 may be inserted and thereby lock arm 7 at any desired angle.

The casing 1 is provided with a projection 13 acting as a journal box upon the shaft 14 connected with the pinion 15 and with the flexible driving shaft 16. The shaft 16 is adapted to extend through the handle 9 between the conduits or pipes 17 and 18 (Figures 2 and 4). Casing 1 is also provided with a hollow boss 19 to which the pipe 20 is connected, said pipe in turn being connected to the pipe or conduit 17. The pipe or conduit 17 is connected to a source of rarefaction or suction, as for instance, a suction pump (not shown). Casing 1 is also provided with an aperture or opening 21 through which the shaft 22 extends, said shaft being hollow and carrying a sprinkler member 23 at the inner end. The outer end is connected in any suitable manner with the flexible hose 23 which in turn is connected through pipe 24 with the pipe 18, whereby water or water and a detergent may be directed to a point within the casing 1, and as shown, to a point substantially centrally of the brush 25. The brush 25, as shown particularly in Fig. 3, is irregular in shape, though provided with a number of arc-shaped sections 26 and 27, said sections being connected together, as clearly shown in Fig. 3, and in turn being connected to the gear wheel 28 through arms 29. Preferably ordinary screws 30 act to clamp the arms 29 to the gear wheel 28, whereby the parts may be removed at any time for repair or replacement. The irregular or arc-shaped arrangement of the brush is to cause the brush to engage a larger surface as it rotates and at the same time cause sections to pass intermittently over the same surface. When water and a detergent has been discharged into the space within the brush a washing and cleaning action is produced by the rotation of the brush 25. As the parts continue to

function the liquid will gradually move outwardly and be drawn or sucked up through the flexible tubes 31. These tubes discharge into an annular space 32, said space being in free communication with pipe 20. A partition 33 is provided within the casing 1, said partition at one section acting to hold the tubes 31 in place by friction, although the tubes may be held in some other manner. 10 5 An outer peripheral rubber wall 34 is also provided, said wall being arranged exteriorly of all of the tubes 31. This wall is positioned so that the edge will engage the surface being cleaned slightly before or at the same 15 time that the bristles 25 engage the surface to be cleaned. In this way all of the space within the wall 34 is subject to the cleaning action of the brush 25 and to the suction above-mentioned, whereby the water, detergent, dirt and other matter picked up will be 20 automatically carried off. By reason of this construction and action the device may be moved over a floor or wall and the floor or wall cleaned without wetting any other part 25 than that being cleaned. Also, by reason of the suction the floor after being cleaned will be substantially dry. In case the suction should become too great and have a tendency to cause the tubes 31 to collapse, air valve 35 30 (Fig. 5) will function. This valve includes a stopper 36, a spring 37 for normally holding the stopper closed, and a supporting ring 38 for holding the spring in place. When the rarefaction reaches a certain point this 35 valve will open and thereby cause the tubes 31 to function in the usual manner as air is let into the space adjacent the brush so that air, water, etc. may move toward the tubes 31. 40 As illustrated in Fig. 3 there is provided a group of bristles 39 in each corner of the casing 1, said bristles acting as brushes for loosening the dirt. As illustrated in Fig. 2, the tubular shaft 22 and its sprinkler head 23 act in the double capacity of means for dispensing water to a point within the brush 25 45 and also as means for supporting the gear wheel 28, whereby the brush may be readily supported and rotated by pinion 15. 50 In operation the handle 9 is grasped and the device moved over the floor or other surface. While this is being done the brush 25 is rotated through the action of the flexible shaft 16 driven by an electric motor or any suitable power (not shown). At the same time 55 that the brush rotates water, and if desired, a detergent, is discharged through nozzle 23. As the brush, water and detergent act to clean the surface suction withdraws the water, detergent and matter removed through the tubes 31, so that the floor or other surface is washed and substantially dried as the device moves thereover.

What I claim is:—

1. A surface washing device, comprising 60 a casing open on the bottom, a suction tube

connected to the upper part of the casing for applying rarefaction in the casing, means for directing a washing liquid into the casing, a brush rotatably mounted in the casing, means extending into the casing for rotating said brush, and a plurality of flexible tubular members carried by the casing at the periphery for causing the suction to act substantially in the plane of the outer end of the bristles of said brush. 75

2. A surface washing machine, including a rotary brush, a series of flexible suction tubes arranged around the brush so as to enclose the brush, and means for applying suction through said tubes to the surface engaged by said brush. 80

3. A surface washing machine, including a casing open at the bottom, a brush rotatably mounted in the casing and projecting to a plane below the bottom of the casing, an annular flexible structure formed of a plurality of tubes carried by the casing and extending to the plane of the outer end of the bristles of the brush, means for applying suction to said tubes for drawing up matter from within the casing, and means for driving said brush. 90

4. A surface washing machine, including a rotatable brush, means for transmitting power to the brush for rotating the same, means for discharging a liquid washing solution adjacent the brush so that the brush may use the solution in its action, a ring formed of a plurality of independent flexible tubes surrounding the brush and means for applying suction to said tubes for removing the liquid and all particles suspended in the liquid from the surface being operated upon. 95

5. A surface washing machine including a substantially rectangular frame, a double row of flexible tubes carried by said frame at its periphery, a suction conduit connected with said tubes, a brush carried by said frame, said brush being ring shaped and positioned within the confines of said rows of tubes, means for rotating said brush, and means for discharging a liquid within the confines of said rows of tubes. 105

6. A surface washing machine including a casing open at the bottom, a ring formed of a plurality of flexible substantially vertical tubes carried by said casing and extending from the bottom thereof towards the surface to be cleaned, a brush arranged within said ring, a gear wheel connected with said brush, means for rotatably supporting said gear wheel, said last mentioned means being hollow and acting as a conduit for directing liquid to a position within the confines of said ring, a pinion meshing with said gear wheel, a flexible driving member connected with said pinion for rotating said pinion, tubular means for applying suction through said ring to the surface to be cleaned whereby 110 115 120 125 130

a liquid and the particles suspended in the liquid may be drawn away from said brush.

7. A surface washing machine comprising a casing having a closed top and an open bottom, a ring formed of a plurality of flexible substantially vertical tubes carried by said casing and projecting from said bottom, a rotatable brush arranged within said ring, means for rotating said brush, a suction conduit connected with said ring and means for directing liquid to a position within said casing.
